EXPULSION TYPE ARRESTER

Clifford W. Petersen, Wauwatosa, Wis., assignor
to McGraw Electric Company, Milwaukee, Wis.,
a corporation of Delaware

Application September 26, 1951, Serial No. 248,337

7 Claims. (Cl. 313—180)

1

This invention relates to electrical discharge devices, and more particularly to lightning arresters of the expulsion type for use on an electric power distribution system.

The present invention may be incorporated in a housing structure similar to that shown in Patent No. 2,429,533, granted to Herman O. Stoelting, on October 21, 1947 and assigned to the assignee of the present invention, and constitutes a novel improvement over that patented structure.

Effective operation of an expulsion type lightning arrester depends upon its ability to produce copious quantities of arc-extinguishing gases at a pressure sufficient for blocking follow current while concurrently providing a relatively cool and de-ionizing atmosphere for quenching conductive arc-sustaining gases.

It is, therefore, a general object of the present invention to provide a novel expulsion tube for lightning arresters with a bore in the nature of a cone having its apex positioned to provide a constricted cross section proximate to the upper electrode and gradually flaring downwardly towards the lower electrode, thereby to provide an expulsion arrester with relatively confined portions for extinguishing low-current arcs, in addition to providing a chamber capable of evolving copious quantities of arc-extinguishing gases for quenching high-current arcs and effectively blocking follow current.

A subordinate object of this invention is to provide a novel expulsion tube for lightning arresters which utilizes a flared or tapered bore cross section in which the cross section may take any one of a number of forms providing a narrowly constricted portion, or portions, defining a relatively distended portion.

Referring now to the drawings which accompany this specification:

Fig. 1 is a longitudinal view, partially in section, of the expulsion-type arrester depicting the preferred embodiment of the present invention.

Fig. 2 is a cross-section taken along lines 2—2 of Fig. 1.

Fig. 3 is a cross-section taken along lines 3—3 of Fig. 1.

Fig. 4 is a perspective view of a semi-cylindrical half-portion of the novel expulsion tube.

Fig. 5 is an end view of another form of the novel expulsion tube.

Fig. 6 is a perspective view of another embodiment of a half-portion of the novel expulsion tube.

Fig. 7 is an end view of a further embodiment of the novel expulsion tube.

2

Fig. 8 is an end view of still another embodiment of the novel expulsion tube.

Referring particularly to Fig. 1, the preferred embodiment constitutes a housing 1 of dielectric material—usually porcelain—having a chamber 2, which is nearly coextensive lengthwise with the housing and open at the lower end, and closed at the upper end except for an aperture 3, which aperture accommodates a stud 4. The stud is electrically connected to a washer 5 making contact with an elongated electrode member 6 clamped to the lower end of a petticoat insulator 7. The insulator 7 is anchored to the upper end of the stud 4, which is firmly embedded therein. A line terminal 8 is fastened to the upper extremity of the insulator 7, and is adapted to engage a conductor wire connecting with the power line that is to be protected. An electrode 9 is secured to the upper end of the insulator 7 making electrical contact with the terminal member 8 concurrently serving to hold this electrode member in operating position. An open-spark gap 10 is formed by the spacing of the free ends of both electrode members 6 and 9. Though an open spark-gap arrangement is preferable, it is within the province of this invention to provide internal spark-gap electrodes (not shown). The spark-gap does not constitute a part of the present invention, but is necessary for isolating the novel expulsion tube from the line terminal 8, thereby preventing leakage currents from flowing to ground through the expulsion tube and associated parts.

A gasket 11 may be provided as a clamping cushion between the insulator 7 and the housing member 1 to prevent chipping of the porcelain when the parts are drawn together. This gasket also acts as a moisture-proof seal.

The components shown assembled within the chamber 2 include a metal electrode plug 12. The plug 12 is threaded externally to engage with a complimentary internally threaded tubular retainer member 13 made of insulating material, preferably horn fiber. The tubular retainer member 13 is reinforced by a metal sleeve 14 surrounding that member, the upper end of which is at a plane approximately level with the plane of the lower extremity of the plug 12. The fiber tubular retainer member 13 is preferably extended above the plug 12 to provide a chamber 13a, which chamber provides a convenient means for increasing the flashover distance between the plug and the sleeve 14, thereby confining the arc within the novel expulsion tube hereinafter described, where it may be properly extinguished. The lower end of the retainer member 13 is

externally threaded to engage a flanged fitting 15, which serves concurrently as a closure for the chamber 2, as a support for the novel arc-extinguishing tube hereinafter described, and as a lower terminal member to which a ground wire (not shown) may be connected. A gasket 16 is provided between the porcelain housing 1 and the fitting 15 to act as a cushion for preventing breakage or chipping of the porcelain.

The metallic fitting 15 is provided with a discharge port 17 for releasing gases to the atmosphere. A lower washer-like electrode member 18 is positioned concentrically of the gasket 16 and in electrical contact with the fitting 15. The fitting is also provided with a means for connecting the arrester, with ground shown here as a solderless connector in the form of a bolt 19 engaging a complementary threaded opening in the fitting 15. The substantially flat surface area 20 of the fitting serves to support the novel expulsion tube as hereinafter described.

The preferred embodiment of the novel expulsion tube will be described with reference to Figs. 1, 2, 3, and 4. The novel expulsion tube 25 is preferably of horn fibre or equivalent arc-extinguishing material, and is preferably split longitudinally to form two semi-cylindrical half-portions 25a and 25b, respectively, which are held together by the tubular retainer member 13. At the upper end of the expulsion tube, preferably in contact with the plug 12, and gripped between the two half-portions 25a and 25b of the expulsion tube, is a cylindrical metal insert 26 which serves as a spark and arc electrode.

The tube 25 has an expulsion chamber consisting of a slot-like passageway trending downwardly from the lower surface of the electrode 26, and terminating at the lower extremity of the tube, where it connects with the discharge port 17 of the fitting 15. The over-all appearance of the expulsion chamber constitutes one of the important novel features characterizing this invention. From a manufacturing standpoint, it is economical to provide one of the half-portions 25b in the form of a semi-cylinder having a substantially flat surface 27 throughout its entire length except for a grooved portion 28 at one end arranged to receive the cylindrical insert 26. The cross-section of half-portion 25b is shown in Figs. 2 and 3.

Referring now to half-portion 25a, the slot-like expulsion chamber or passageway 30 provides a cross-section that gradually flares downwardly as shown in Figs. 1 and 4 from a relatively constricted portion 31 connecting with the lower extremity of the electrode 26 to the relatively distended portion 32 connecting with the discharge port 17. The flare is preferably semi-conical in nature; viz., providing a gradually increasing depth as well as a gradually increasing width intermediate of its end portions 31 and 32, respectively. From an examination of Fig. 4 it will be seen that the cross section configuration is approximately sectorial—and is narrowly constricted along one edge portion and considerably distended along the opposite edge portion. The narrowly constricted edge portion is identified by reference numeral 30a, whereas the distended portion of the passageway is identified by reference numeral 30b. The configuration takes substantially the same form as the configuration of one of the half-portions disclosed in the above mentioned patent granted to H. O. Stoelting, over which the present invention constitutes an improvement.

It will be apparent that an arc forming at the

upper electrode 26 originates at a very restricted portion 31 of the expulsion chamber, proximate to the apex of the semi-conical passageway 30. Thus, even the smallest amount of gas created will set up a considerable pressure almost instantly because of the area restriction. This pressure creates a very dense gas which serves to block the flow of follow-current. Thus, pressures built up by the surge alone should be sufficient to prevent follow-current. The relative slowness of the gas movement towards the discharge end will maintain a pressure for a sufficient length of time to prevent follow-current from starting until the arc has been properly extinguished. The arc, moving towards the ground connection, will follow a constricted path—the narrowly constricted edge portion 30a. Pressures built up here tend to "blow" the arc towards the center of the passageway where they will be cooled very rapidly. The cooled, de-ionized gases will then be expelled from the expulsion chamber through the discharge port 17. Since the extinguishing gases created by action of the arc on the horn fibre is directed downwardly towards the end supported by the fitting 15 the gases will be expelled at a place where the arrester is mechanically strongest.

Referring now to Fig. 5, it will be apparent that an effective expulsion tube may consist of two substantially identical half-portions 25a and 25c, which are constructed in left and right hand relationship. The arc passageway 35 provides a sectorial cross section which gradually flares downwardly from the electrode 26 towards the lower discharge end of the novel expulsion tube as viewed in Fig. 5. As was stated above, it is preferable to slot each of the half-portions 25a and 25c to provide a gradually increasing depth as well as width. This particular structure may be provided where it is desired to have an arc passageway that provides a relatively larger gas discharge portion in substantially the same length tube as suggested by the preferred embodiment.

Another embodiment of the novel lightning arrester expulsion tube is shown in Figs. 6 and 7, wherein a novel half-portion 25d is mated with a half-portion 25b previously described. The novel half-portion 25d includes an arcing slot or passageway 36 having a cross-section in the nature of a half-round or semi-elliptical which is particularly shown in the end view, Fig. 7. The half-round passageway, like the sectorial passageway of the preferred embodiment, gradually flares downwardly from the lower extremity of the electrode 26 to the discharge portion connected to the lower electrode 18. Again, the passageway 36 preferably takes the form of a semi-conical chute providing a relatively constricted portion 37 which is approximately at the apex, and flaring downwardly with both a gradually increasing depth and width to provide a relatively distended cross section at the discharge end. In this embodiment, two relatively constricted edges 36a and 36b are provided with a distended portion 38 intermediate thereof.

The structure illustrated in Fig. 7 utilizes two half-portions 25b and 25d to provide a cylindrical expulsion tube which may be positioned in the tubular retainer member 31 and intermediate of the plug 12 and the lower electrode 18. The insert 26 is gripped between the mating half-portions at the upper end making electrical contact with the metallic plug 12.

A further embodiment is illustrated in Fig. 8

and is provided by mating two substantially identical half-portions 25d. Obviously, this is a less expensive structure from a manufacturing standpoint, inasmuch as the mating half-portions 25d do not have to be in left or right hand relationship as the half-portions 25a and 25c of the structure shown in Fig. 5.

All of the above described embodiments operate in substantially the same manner, and the mode of operation will be described with reference to the preferred embodiment disclosed in Fig. 1. When a surge occurs on the power line and is of high enough potential, it will simultaneously spark-over the external gap 10 and the internal expulsion gap between the arcing electrode 26 and the lower electrode 18 which is electrically connected with ground through the fitting 15.

Under certain conditions the surge may initiate the flow of power follow-current making it necessary to extinguish the power follow-current arc in order that the arrester may return to its original operating condition. To accomplish this, this invention contemplates the use of the novel expulsion tube described above and contained within the retainer member 13 and extending laterally between the electrode plug 12 and the lower electrode 18. The power current, which is normally 60-cycle current, produces an arc that tends to follow the path taken by the abnormal surge voltage that has sparked over the arrester electrodes, and will tend to be confined to the relatively constricted portions of the passageway 30a where the pressures built up will limit, cool and rapidly extinguish this follow-current at first current zero.

The novel flared passageway provided by this invention makes use of an expulsion gap that requires no intermediate electrodes, but operates to effectively block power follow-current and extinguish arcs produced by surge voltages of both very low and high magnitudes. As was described in the above mentioned patent granted to Stoeling, a passageway configuration providing both a relatively constricted portion and a distended portion serves to provide an initiating means for arcing at the constricted portion wherein the erosive action of the arc is confined to the distended portion where it has the least effect towards terminating the useful life of the expulsion tube. In addition, the present structure provides a further constricted portion at the arc initiating area proximate to the electrode 26 where relatively low current arcs may be immediately extinguished, at the same time providing an effective blocking means to follow-current, while high magnitude arcs may be effectively extinguished in the relatively distended portion approaching the discharge end of the passageway after initial spark-over along the constricted edge of the passageway.

I claim:

1. A lightning arrester of the expulsion type including, two spaced electrodes, an expulsion tube intermediate said electrodes, said tube embodying gas evolving material defining a chamber tapered longitudinally between said electrodes and providing a constricted aperture adjacent one electrode and a distended aperture adjacent the other electrode, whereby back gas pressure in said chamber is effective to extinguish arcs and concurrently block current following either high or low magnitude arcing between said electrodes.

2. A lightning arrester of the expulsion type including, two spaced electrodes, an expulsion

tube intermediate said electrodes, said tube embodying gas evolving material defining a chamber tapered longitudinally between said electrodes and providing a constricted aperture adjacent one electrode and a distended aperture adjacent the other electrode, the transverse cross-section of said chamber being an aperture of elongated slot-like configuration, said chamber being narrowly constricted widthwise substantially throughout its length on at least one portion of its cross-sectional area, and comparatively distended widthwise substantially throughout its length at a portion of its cross-sectional area laterally of the first mentioned portion, whereby back gas pressure in said chamber is effective to extinguish arcs and concurrently block current following either high or low magnitude arcing between said electrodes.

3. A lightning arrester of the expulsion type including, two spaced electrodes, an expulsion tube intermediate said electrodes, said tube embodying gas evolving material and defining a chamber tapered longitudinally between said electrodes and providing a constricted aperture adjacent one electrode and a distended aperture adjacent the other electrode, the taper of said chamber having a major dimension as measured transversely to the longitudinal axis of said chamber and a minor dimension substantially normal to said major dimension, whereby back gas pressure in said chamber is effective to extinguish arcs and concurrently block current following either high or low magnitude arcing between said electrodes.

4. A lightning arrester of the expulsion type including, two spaced electrodes, an expulsion tube intermediate said electrodes, said tube embodying gas evolving material and defining a chamber extending between said electrodes, said chamber having an elongated cross-sectional delineation including an apex at one end of the elongation and a relatively wide base portion at the other end, said chamber being tapered longitudinally between said electrodes, whereby back gas pressure in said chamber is effective to extinguish arcs and concurrently block current following either high or low magnitude arcing between said electrodes.

5. A lightning arrester of the expulsion type including, two spaced electrodes, an expulsion tube intermediate said electrodes, said tube embodying gas evolving material and defining a chamber extending between said electrodes, said chamber having an elongated transverse cross-section extending substantially through its length, one side of said chamber being a flat surface and the other side being grooved to provide an apex at one side of said cross-section and a relatively distended portion at the other side, said chamber being tapered longitudinally between said electrodes, whereby back gas pressure in said chamber is effective to extinguish arcs and concurrently block current following either high or low magnitude arcing between said electrodes.

6. A lightning arrester of the expulsion type including, two spaced electrodes, an expulsion tube intermediate said electrodes, said tube embodying gas evolving material and defining a chamber extending longitudinally between said electrodes, said chamber having a transverse cross-section extending substantially through its length and defining a substantially elliptical aperture including two opposed constricted portions and a relatively distended portion intermediate said constricted portions, said chamber be-

ing tapered longitudinally between said electrodes, whereby back gas pressure in said chamber is effective to extinguish arcs and concurrently block current following either high or low magnitude arcing between said electrodes.

7. A lightning arrester of the expulsion type including, two spaced electrodes, an expulsion tube intermediate said tube embodying gas evolving material and defining a chamber extending between said electrodes, said chamber having an elongated transverse cross-section extending substantially through its length, one side of said chamber being a flat surface and the other side

5

being grooved to jointly provide two opposed constricted portions with said flat surface and a relatively distended portion intermediate said constricted portions, said chamber being tapered longitudinally between said electrodes, whereby back gas pressure in said chamber is effective to extinguish arcs and concurrently block current following either high or low magnitude arcing between said electrodes.
